(57) **CLAIM**

The ornamental design for a valve gear operator, as shown and described.

DESCRIPTION

FIG. 1 is a perspective view of a gear operator showing our new design with a handle shown in broken lines and mounted to a valve also shown in broken lines.

FIG. 2 is a front elevational view thereof.

FIG. 3 is a rear elevational view thereof.

FIG. 4 is a side elevational view thereof.

FIG. 5 is a side elevational view a side opposite that shown in FIG. 4.

FIG. 6 is a top plan view thereof; and,

FIG. 7 is a bottom plan view thereof.

The broken lines shown in FIG. 1 are for purposes of illustrating environment only and form no part of the claimed design.
